UNITED STATES PATENT OFFICE.

WILLIAM GEORGE LANDELLS, OF COBURG, VICTORIA, AUSTRALIA.

SELF-HEATING ADJUSTABLE CATTLE-BRANDING APPLIANCE.

No. 926,881.

Specification of Letters Patent.

Patented July 6, 1909.

Application filed March 18, 1908. Serial No. 421,880.

To all whom it may concern:

Be it known that I, WILLIAM GEORGE LANDELLS, a subject of the King of Great Britain, residing at Service street, Coburg, in the State of Victoria, Commonwealth of Australia, have invented a certain new Improved Self-Heating Adjustable Cattle-Branding Appliance, of which the following is a specification.

10 My invention relates to that class of self-heating branding-irons in which the brand is kept continuously and uniformly-heated.

The object of the invention is to provide novel features in the construction of certain 15 parts for pre-determining the depth to which the brand imprint will be made in the hide of an animal.

Another object of the invention is to provide a novel construction of automatic feeding device in the tubular handle-reservoir of a self-heating branding iron whereby a constant and even flow of liquid fuel will be forced under air pressure from the tubular handle reservoir to the burner irrespective 25 of the angle or position in which the iron is held.

The invention further provides a novel construction and arrangement of means for the quick interchanging and locking of removable branding plates of the branding box.

In the accompanying drawings illustrative of my invention Figure 1, represents an enlarged vertical sectional view of the improved branding iron. Fig. 2, is a vertical elevation of the branding box and the adjustable guard frame used therewith. Fig. 3, is a plan of the rear perforated wall of the branding box with the adjustable guard frame shown embracing the removable tubular frame. Fig. 4, is a plan of the branding box and the adjustable guard frame showing the branding plates with the raised letters or numerals on the outer face thereof. Fig. 5, 45 is also a plan of the branding box showing the opening in its face. In this view the branding plates and the adjustable guard frame are not shown. Fig. 6, is an enlarged sectional plan of my branding iron taken 50 upon the horizontal line (1, 1,) of Fig. 1.

Similar numerals of reference denote like parts in all the views.

My invention of a self-heating branding

iron consists of an adjustable guard frame having the four arms (2), a rectangular shaped perforated guard (3) and the tubular sleeve clamp (4). This clamp is comprised of the projecting end pieces (5) and (6) through which I drill a hole and insert the bolt (7) carrying a thumb nut so that said clamp can be made secure upon a removable tubular frame as clearly shown at Figs. 3 and 6. About midlength of said arms (2) I fix a guide collar (8) to embrace said removable tubular frame (10) consisting of two end sleeves (10') and (11) formed conjointly with the four equidistant ribs (12) having the openings between them as at (13) in Figs. 1 and 2. The sleeve (10') is bayonet jointed with the tubular portion (16) of the branding box (15) and the sleeve (11) is similarly jointed with the liquid fuel reservoir (28). Upon the sleeve (11) are cut several divisions of an inch as at (14) ranging from one sixteenth and upward, so that the inner end of the adjustable guard frame can be set to any division by first pre-determining the depth to which the brand imprint is to be made in the hide of an animal.

The letters or numerals form part of the branding plates hereinafter described and project beyond the face of said plates about a quarter of an inch.

The branding box (15) which is a box like casting, is provided with the opening (17) in the outer face and the tubular portion (16) thereof has a number of holes such as (18) to admit air to the interior of the branding box so that the burner flame while heating the branding plates will be continuously supplied with oxygen or atmospheric air. A V-shaped flame distributer (19) suitably secured across the inner mouth of said spigot distributes the burner flame upon the flat backs of the three branding plates (20), (21), and (22), each of which has rabbeted side edges fitting into and against each other as shown at Figs. 1 and 4 to prevent any escape of the burner flame between the joints of said plates. A fastening lever (27) is pivoted at (26) near one end of the branding box (15) to retain the branding plates in a crowded or closed up position while the thumb screw (27^a) prevents the fastening lever from swinging outwardly. These plates have their ends under the rabbeted guide

strips (23) and (24) suitably secured to the outer face of the branding box and one edge of the plate (20) fits under the rabbeted strip (25). This lever engages with the outer rabbeted edge of the branding plate (22) and also with the rabbeted end portion of the strip (24) and when this lever is swung outward these plates may be slid out of the positions shown and others substituted therefor. The tubular handle reservoir (28) holds the liquid fuel, preferably kerosene, which is introduced into the reservoir through the fuel inlet (40). The bottom end of said reservoir is provided with a flanged screw threaded cap (37) in which is tightly inserted an air-pump, consisting of the tube (29) provided with the air passage (30) and the perforated cap thimble (33) while the non-return air valve (31) prevents the compressed air from returning again to the pump. (32) is a compression spring for valve (31). The plunger rod (34) passes through the stuffing box (38) and screw gland (39) and is provided with the leather gasket (35) held thereon by the two nuts (36).

For the introduction of the liquid fuel to the reservoir I construct the fuel inlet (40) in which is fixed the wire gauze oil strainer (41) for the reservoir while the latter is being filled with kerosene. Through the inlet cap (42) I drill a hole which contains a seat (44) for the conically pointed thumb screw valve (43) which can be operated so as to allow of the air pressure within the reservoir being instantaneously reduced or released for regulating the intensity of the burner flame. (46) is a sleeve of felt or asbestos fitting tightly over the reservoir to act as a non-conductor of heat whereby the operator can conveniently handle the implement.

The feeding device of my iron shown at Fig. 1, consists of the central feed tube (47) which fits tightly in a hole drilled in the fixed head of the reservoir and priming cup (55). One end of this tube then enters the hole or passage-way (53) of the burner block (56) while the other end of said tube projects into the reservoir (28). This feed tube is provided with two circular rows of feed ports (51) and (52) which communicate with the passage-way of said tube and the burner block inlet passage (53). Upon the tube (47) I mount the rotatory sliding sleeve (48) which is free to automatically move or swing axially to any position. Said feed tube is also provided with the screw threaded end cap (54) which serves to limit the length of travel of said sleeve (48) to which I secure two hollow feed arms (49) and (50) to continuously admit liquid fuel to the said feed tube in whatever position the implement is held by the operator. The hole or passage-way (53) aforementioned is drilled in said burner block in which I also drill the hole or passage-way (64). In the forward ends of

the holes (53) and (64) I secure the inner ends of the oppositely arranged pipes (65) and (66), while to the outer ends of said pipes I securely fix the diamond shaped hollow junction piece (67). The rear edge of said burner block is set hard against the rim of the priming cup and is retained in the position shown by the end of the central feed tube fixed in said passage-way (53) of the burner block. The priming cup (55) is bulb-shaped and is provided with a flange (55^A) which is rigidly fixed to the head of the reservoir. (57) is the removable tubular shield inclosing these pipes (65) and (66) also the junction piece, and is bayonet jointed with the burner block by means of the two L-shaped slots as at (63), thereby permitting of the easy removal of said shield so that access may be had to the parts inclosed therein. Said shield (57) is provided with openings (58) and (59) spaced equally all around to admit atmospheric air to the burner flame. I form the nozzle (60) upon this shield so as to fit loosely into the central aperture of the deflecting disk (61) which is made with pivot axles carried in holes made in the removable tubular frame. (68) is the vapor burner nipple screw threaded to fit into the outlet passage (64) of the burner block (56) and provided with the needle vapor discharge (69).

The working of my self-heating branding iron is as follows:—Where it is required to burn letters to a depth of say one-eighth of an inch in the hides of cattle, I adjust the guard frame so that the end of sleeve (4) will be on the first eighth of the divisions marked off as at (14) Fig. 2 on the removable tubular frame 10 and so that the outer face of the guard (3) will be level with the dotted line (80). The branding letters therefore project beyond the outer plane of the guard frame 3. The thumb screw (7) with nut thereon is then tightened to clamp the adjustable guard frame firmly in position upon said tubular frame. The liquid fuel is then introduced into the reservoir (28) through the inlet (40) by removing the cap (42). I then hold the implement in a vertical position and in the priming cup (55) I then place a small quantity of methylated spirit, which when ignited by means of a match heats the burner block (56), pipes (65) and (66) and junction-piece (67). This heating starts the flow of liquid fuel vapor from the passage-way (69) of the nipple (68). The plunger rod (34) carrying the gasket (35) is then pushed inwardly so as to pump atmospheric air through the passage way (30) and as it is drawn outwardly a partial vacuum is created in the upper end of said tube (29). As the air enters around and between the plunger rod (34) and the loose packing of the stuffing box (38) it is therefore free to pass the leather gasket (35) to the forward vacuum part of said pump tube (29), wherefrom it is forced past the valve (31).

through the air holes in the cap thimble (33) into the reservoir (28), when the plunger rod (34) is again pushed inwardly. The air pressure, which may now be increased by pumping air into the reservoir (28), will force the liquid fuel into the passage-way of long hollow arm (49) which for the time being is partly suspended in the liquid fuel while the implement is held vertically. The liquid fuel acted upon by the air pressure is then forced through the ports (52) which are now in communication with the passage-way of said hollow feed arm (49) and that of the central feed tube (47), the other ports having been shut off from communication with the reservoir (28) by the upper end portion of the sleeve (48). From the passage-ways of said long hollow arm (49), ports (52), and central feed tube (47), the liquid fuel passes into the pipe (66), and entering the junction piece (67) it is divided into two streams which on exit therefrom to the pipe (65) and outlet passage way (64) again unite. While passing through the burner block passages (53) and (64), pipes (66) and (65), and said junction piece (67), the liquid fuel is vaporized by the burner flame and upon ignition of the vapor issuing from the passage exit (69) of the nipple (68) an intense flame fed by the external air entering through the openings (13), (58) and (59) completely envelops and heats the pipes (65) and (66) and junction piece (67), so as to prime and generate the liquid fuel into vapor. The flame then issues through the nozzle (60) and enters the perforated branding box (15) and impinges upon the rear faces of the branding plates; the flame is not only equally distributed thereupon by means of the V shaped distributor but is also prevented from passing between the joints of the plates by their rabbeted side edges, fitting into one another. Any return flame will be deflected back again into the branding box (15) by the deflecting disk (61). The same result is attained when the branding iron is held horizontally or inclined downwardly in which case the rotatory sliding sleeve (48) carrying the two hollow arms (49) and (50) slides to a position against the inner end of the reservoir, thereby opening the ports (51) to the passage way of the short hollow arm (50) which now depends in the liquid fuel. The downward sliding movement having altered the position of the sleeve upon the central feed tube (47) shuts off the ports (52) and the long hollow arm (49) from communication with the liquid fuel contained in the tubular handle reservoir.

I wish it to be here understood that the hollow feed-arms (49) and (50) upon the sleeve (48) will not only rotate with said sleeve (48) in any axial position, but will also follow the oil around the inner circumference of the reservoir (28) as the implement is revolvably moved or held in any po-

sition, and that the burning in of the letters or numerals to the required depth is continued until the perforated guard (3) bears hard against the animal's hide.

Having now described my invention, what I claim as new and desire to secure by Letters Patent is:

1. A self-heating branding iron comprising a tubular handle reservoir, a tubular frame detachably connected thereto, an adjustable guard frame, a perforated guard connected with the outer end of said frame, and an adjustable clamp securing said frame to the tubular frame. 75

2. In a self-heating branding iron, an automatic oil feeding device of the character described, comprising a central feed tube, one end of which enters the burner block passage (53), while the other end passes through the priming cup (55), finally projecting into the tubular handle reservoir, wherein it is provided with the flanged end cap (54), two circular rows of feed ports in the end of said tube situated within the reservoir, a rotatory sliding sleeve mounted upon the end of the feed tube, extending over the feed ports and provided with the two hollow feed arms communicating with said feed tube and alternately with each row of said feed ports, substantially as described. 80 85 90 95

3. In a device of the character described, a feed tube having one end connected with the passage-way (53) of the burner block and the other end projected through the priming-cup and into the tubular handle of 100 the reservoir wherein it is closed by the flanged end cap (54) and provided with the circular rows of feed ports (51) and (52); the rotatory sliding sleeve having the two hollow feed arms (49) and (50) operating with 105 said sleeve revolvably within the reservoir for the continuous supply of liquid fuel from the reservoir to the burner block and its passages, vaporizing pipes and vapor discharge nipple through either row of said 110 feed ports according to the upward or downward direction given to the implement by the operator, substantially as described.

4. In a device of the character described, a branding-box with an opening in its top, rabbeted strips at the sides, and one strip at one end of said opening, movable and interchangeable branding plates having their edges slidably held in said rabbeted portions, said plates having oppositely rabbeted 115 meeting edges forming overlapping portions, and a pivoted fastening lever held in position by a thumb-screw and bearing against the rabbeted edge of the outer branding plate (22), substantially as described. 120 125

5. In a device of the character described, a branding-box, side and end rabbeted strips upon the front face thereof to form a bed for holding the branding plates in engagement with one another and preventing any 130

escape of flame between them, a fastening lever held by a thumb screw for keeping said lever and plates in position and a tubular portion upon the said branding box to fit into the removable tubular frame and connect therewith by a bayonet joint, substantially as described.

In testimony whereof I have hereunto set my hand in presence of two subscribing witnesses.

WILLIAM GEORGE LANDELLS.
